UNITED STATES PATENT OFFICE.

F. AUGUST VOIGT, OF ST. LOUIS, MISSOURI.

STREET POUNDER OR RAMMER.

SPECIFICATION forming part of Letters Patent No. 295,213, dated March 18, 1884.

Application filed December 31, 1883. (No model.)

To all whom it may concern:

Be it known that I, F. AUGUST VOIGT, of the city of St. Louis, in the State of Missouri, have invented a certain new and useful Improvement in Street-Pounders, of which the following is a full, clear, and exact description, reference being had to the accompanying drawing, forming part of this specification.

10 The drawing is a perspective view of the tool.

A is the shank or stem of the machine; B, the head, and C the cross-bar or handle. The shank and the main part of the head are made 15 of wrought-iron, the head being faced with steel at B', the steel being welded on. The shank has at the upper part two diametric holes to receive a cross-bar or handle, C, by which the pounder is operated. The purpose 20 of providing two holes for the handle is to allow the accommodation of the same to persons of various heights, so as to increase the efficiency of the workman and avoid putting him to distress or subjecting him to strain.

25 The pounder is made of sufficient weight to deliver a blow of the requisite force by gravity alone without requiring any downward pressure of the workman upon the handle. Thus in the descent the whole attention may be

30 given to guidance of the tool, insuring perfect work in the surface-work of the street. When the pounder is made heavy, it is especially required that the handle shall be of a proper height to suit the workman, for if the handle 35 is too low he will be required to stoop too much, and if the handle is too high the labor will have to be performed chiefly or wholly by the arms, and the workman cannot use his powers to good advantage.

The tool, it will be seen, is very compact, 40 being made entirely of metal, except the handles, and these may be made of metal, too, or of wood. Hitherto pounders for streets have, as far as I know, been made of wood, and have necessarily been cumbrous, obstructing the 45 view of the workmen. Another and more serious objection to the wooden rammer or pounder is that the face wears unevenly, so that smooth and even work cannot be done. The steel face retains its form, and thus the 50 face is or remains perpendicular to the stem after long use.

I have shown a capacity for adjustment of the handle C to two elevations; but do not confine myself to two, as three or more may be 55 provided for by making an additional number of the diametric holes in the stem for the handle. I have shown the tool with two handles, to illustrate the preferred relative position of the holes for the handles. In use but 60 one handle would be inserted.

As a modification, the body may be of cast-iron with a chilled face; but the described construction is believed to be much better.

I claim as my invention—

1. A street rammer or pounder having an iron body and steel or chilled face and cross-handle C, for the purpose set forth.

2. A street rammer or pounder having an iron body, A B, a steel or chilled face, B', and 7c adjustable handle C, substantially as set forth.

F. AUGUST VOIGT.
